(57) **CLAIM**

The ornamental design for an apparatus support device holder, as shown and described.

DESCRIPTION

FIG. 1 is a front view of an apparatus support device holder, FIG. 2 is a rear view of an apparatus support device holder shown in FIG. 1,

FIG. 3 is a right side view of the apparatus support device holder shown in FIG. 1,

FIG. 4 is a left side view of the apparatus support device holder shown in FIG. 1,

FIG. 5 is a right side perspective view of the apparatus support device holder shown in FIG. 1,

FIG. 6 is a left side perspective view of the apparatus support device holder shown in FIG. 1; and,

FIG. 7 is a bottom view of the apparatus support device holder shown in FIG. 1.

The four small protrusions shown on the surface of the locking lever in FIGS. 3 and 4 are ribs extending over the full width of the locking lever. They should be shown in broken lines as they form no part of the claimed design. But, because of their small size, the broken lines can not be shown and therefore are described in this statement for clarity.

The apparatus support device holder is used for supporting an apparatus support device specifically adapted to cradling a particular apparatus such as a wireless phone, GPS, a PDA device, a telephone or other equipment in a convenient position on a smooth surface such as a windshield of a motor vehicle.
